UNITED STATES PATENT OFFICE.

JAMES I. KINKEAD, OF REDDING, CALIFORNIA.

DEVICE FOR TRANSMITTING POWER.

No. 853,553.

Specification of Letters Patent.

Patented May 14, 1907.

Application filed November 28, 1906. Serial No. 345,549.

To all whom it may concern:

Be it known that I, JAMES I. KINKEAD, a citizen of the United States, residing at Redding, in the county of Shasta and State of California, have invented new and useful Improvements in Devices for Transmitting Power, of which the following is a specification.

My invention relates to an apparatus for the application and transmission of power.

It consists in a combination of parts, and details of construction which will be more fully explained by reference to the accompanying drawings, in which—

Figure 1 is a side elevation illustrating my apparatus. Fig. 2 is a plan view of the same. Fig. 3 is a side elevation showing a different application of the power.

My invention is illustrated as follows:

A is a lever fulcrumed as shown at 2. Upon each side of this lever are horizontal parallel tracks 3, and upon these tracks a roller 4 is adapted to travel. The end of the lever contiguous to the roller is raised at an incline as shown at A¹, so that when the roller is moved along upon its track, the central portion will bear upon and depress the inclined portion A¹ of the lever. This will act to raise the opposite end of the lever, and by means of any suitable connections, as links or pitmen 5, connection may be made to transmit the movement of the lever to any mechanism which it is desired to operate, such as a pump, a drill, or other reciprocating device.

The roller 4 may be made of any suitable or desired diameter and weight, and is here shown as connected by a pitman 6 with a source of power. This source of power may be a steam engine or other equivalent motor. As here shown the pitman 6 is connected with a guided cross-head 7, and this with a piston-rod 8 through which power is communicated to move the roller.

The operation of the device will be as follows: The roller being drawn toward the motor, will press upon the inclined portion A¹ of the lever, and by reason of the weight of the roller, this end of the lever will be depressed. The first contact of the roller with the lever meets with such resistance as the weight or mechanism to be moved at the opposite end of the lever applies; the weight of the roller and the power applied to move it being sufficient to move it. As the roller moves forward upon its tracks, it depresses the inclined por-

tion A' of the lever, and thus raises the opposite end with its connected parts. As the inclined portion A' approaches the horizontal position, the power necessary to move the roller over it gradually decreases, and the resulting effect upon the opposite end of the lever is correspondingly increased. It will also be manifest that the leverage applied to move the roller will be, in effect, the distance between the center of the roller and its point of contact, which practically forms a moving fulcrum, so that if the roller be, for instance, six feet in diameter, and connection between the power mechanism is made with the center of the roller, a certain amount of power will be necessary to move the roller independent of the weight to be raised. If the roller be increased to say, 8 feet in diameter, with a radius of 4 feet, and the same weight as before, the leverage upon the roller will be increased, and the power necessary to move it will be correspondingly less. When the roller has completed its forward movement, and depressed the lever, it may be returned by the return reciprocation of the motor, and the end of the lever being thus released, will be raised by the weight at the opposite end of the lever. Such a weight may be represented at 9. Or the weight of the moving parts may be sufficient to depress this end of the lever in unison with the return movement of the roller.

In Fig. 3 I have shown the lever fulcrumed as before at 2, and the power is then applied, and the pitman 5 is connected with the lever A between the fulcrum 2 and the inclined end A' of the lever, making a lever of the second class instead of as in the first case where the connecting rod is outside of the fulcrum which forms a lever of the first class. In this case, the connection may be made as before with any desired apparatus to be reciprocated, and the movement of the roller, depressing the lever A' will depress the pitman and connected parts. The weight 9^a at the outer end of the lever A' is sufficient to depress this end of the lever and to raise the inclined end A' as soon as the roller has returned and the pressure has been relieved. As shown in Fig. 3, the roller 4 is inclosed by an outer cylinder 4^a of larger diameter than the roller. This annulus 4^a practically forms an endless track within which the roller 4 is movable, and while the annulus 4^a rolls upon the parallel tracks 3.

Having thus described my invention, what I claim and desire to secure by Letters Patent is—

1. An apparatus including horizontal parallel tracks, a roller adapted to travel upon said tracks, means for imparting reciprocal movement to the roller, and a lever fulcrumed with relation to the tracks having an upturned end over which the roller is movable whereby the opposite end of the lever is raised by the forward movement of the roller.
2. In an apparatus for the application of power, a fulcrumed lever having an upwardly inclined end, tracks disposed horizontally upon each side of the lever, a roller having its outer ends resting upon the tracks and the central portion movable above the lever, means for imparting a continuous reciprocal movement to the roller whereby said roller is moved back and forth over the tracks, and over the inclined portion of the lever, and connections by which the movement of the lever may be transmitted.
3. In an apparatus for the application and transmission of power, a weighted roller, horizontal tracks upon which it is movable, a reciprocating cross head and means connecting the cross head with the roller whereby said roller is reciprocated over said track, a lever fulcrumed between the tracks having its central portion substantially upon the

same level therewith, and the forward end upturned at an incline whereby the movement of the roller acts to depress the inclined end, means by which said lever is connected with parts to be moved, and a weight by which the lever is returned to its normal position when released from the roller pressure.

4. In an apparatus for the application and transmission of power, horizontally disposed tracks, a cylindrical shell resting upon said tracks, a roller of smaller diameter resting upon the lower side of the shell, connections between the shell and a motor by which the parts are caused to travel backward and forward along the track, a lever fulcrumed between the tracks having one end upturned at an inclination so that the roller shall act upon this inclined end to depress it and raise the opposite end, means connecting the lever with parts to which power is to be transmitted, and a weight by which said parts and lever are returned to the normal position when the roller is retracted.

In testimony whereof I have hereunto set my hand in presence of two subscribing witnesses.

JAMES I. KINKEAD.
